CLAIM

The ornamental design for a memory card holder, as shown and described.

DESCRIPTION

FIG. 1 is a perspective view of a memory card holder that incorporates my new design.

FIG. 2 is a bottom view thereof.

FIG. 3 is a rear view thereof.

FIG. 4 is a top view thereof.

FIG. 5 is a front view thereof.

FIG. 6 is a left-side view thereof; and,

FIG. 7 is a right-side view thereof.
